UNITED STATES PATENT OFFICE.

GEORGE I. ROCKWOOD, OF WORCESTER, MASSACHUSETTS.

CASING FOR ALARM DEVICES.

1,114,528.

Specification of Letters Patent.

Patented Oct. 20, 1914.

Application filed December 31, 1913. Serial No. 809,745.

To all whom it may concern:

Be it known that I, GEORGE I. Rockwood, a citizen of the United States, residing at Worcester, in the county of Worcester and 5 State of Massachusetts, have invented a new and useful Casing for Alarm Devices, of which the following is a specification.

This invention relates to that type of alarm devices used in connection with fire 10 sprinkler systems and the like and involving ordinarily a rotary wheel adapted to be set into rotation by the escape of water to operate a clapper shaft and an electrical attachment for giving a separate alarm.

15 Heretofore, these devices have been made in the form of a casing surrounding the wheel and having a nozzle extending into the casing to discharge the water against the vanes of the wheel and this has had 20 to be connected by piping with a separate casing having a diaphragm for operating the electric alarm. The nozzle constitutes a vent for one of these casings and the other has had to be provided with an 25 other vent. The result of this has been that an appreciable amount of pressure is lost. This is very undesirable as these devices operate only at long intervals, and consequently the clapper shaft is liable to rust 30 and stick so that the full power is required.

The principal object of this invention is to provide a simplified, compact, and inexpensive casing for this purpose serving in itself all the purposes of both of the above 35 mentioned casings and thus eliminating a part of the expense of setting the device up, as well as of manufacturing the parts originally, and also having only one vent so that the loss of pressure from that cause is 40 halved.

Reference is to be had to the accompanying drawings in which,

Figure 1 is an end elevation of a casing constructed in accordance with this invention with the nozzle shown in central longitudinal section; and Fig. 2 is a central sectional view of the device.

The invention is shown in a form in which the casing comprises a single part 10, preferably a casting, having a chamber 11 there- 50 in for receiving the supply pipe 12 at the bottom and having a partition 12^a at one side of this chamber so as to provide a second chamber 13 on the other side of the cas- 55 ing having a discharge outlet 14. This sec-

ond chamber is open at the side. The partition is provided with a hub 15 which can be bored from the open side to provide a seat for a bearing bushing 16. The open side is intended to be closed by a separate 60 cast member having an integral wall or plate 18 for closing that side of the chamber 13. This wall is provided with a bearing 19 for the shaft 20 of the water wheel 21, the other end of this shaft being sup- 65 ported in the bushing 16. The cast member is provided with projecting legs 17 which constitute a skeleton frame-work for sup- 70 porting the device on a wall.

The clapper shaft 22 is in alinement with 70 the shaft 20 and has fixed thereon a hollow eccentric hub 23 loosely surrounding the end of the shaft 20. In this hub on the shaft 20 is an eccentric member 24 designed to give a sharp blow to the low part of the 75 eccentric hub when the shaft 20 starts, and thus start the clapper shaft even if it sticks.

The chamber 11 is provided with an off- 80 set 25 which surrounds a filter 26 and communicates with a nozzle 27 arranged in the plane of the wheel 21. This discharges water directly against the vanes of the wheel 21 to turn the same for the purpose of giving an alarm. Any ordinary alarm means connected with the clapper shaft 22 can be 85 employed. The end of the chamber 11 in the casting 10 is also shown as open originally and closed by a movable diaphragm 31 adapted to be operated by the pressure of water to move a plunger 32 and operate 90 an electric switch 33 to close an alarm bell circuit 34. These parts are mounted on a plate 35 located over the diaphragm. With this construction, the chambers for operating the electric alarm and for containing the 95 wheel 21 are formed in a single member. There is no finishing to be done, therefore, and no fitting of parts to connect these two casings, and no complications are introduced in the placing of the plate 18, the nozzle 27, 100 or the electrical alarm. The nozzle 27 vents the whole operating device and therefore the loss of pressure due to this is kept at a minimum.

Although I have illustrated and described 105 only a single embodiment of the invention, I am aware of the fact that many modifications can be made therein by any person skilled in the art without departing from the scope of the invention as expressed in 110

the claims. Therefore, I do not wish to be limited to the details herein shown and described, but what I do claim is:—

1. As an article of manufacture, a casing 5 for the purpose described comprising a main chamber for receiving water from a pipe or the like, said chamber having a tangent offset beyond one end thereof, a nozzle in said offset, a wheel rotatably supported by said 10 casing concentric with said chamber and beyond its end in position for receiving the discharge of water from said nozzle, and a diaphragm in said chamber parallel with the plane of the wheel for operating 15 an electric alarm.
2. As an article of manufacture, a device for the purpose described comprising a casting having an upright partition there-through, a complete chamber on one side of 20 the partition within the casting, a chamber on the other side of the partition, an offset from the first named chamber in alinement with the second chamber, a wheel rotatably supported in the second chamber, and a nozzle 25

40 zle supported in said offset in position to 25 direct its discharge against said wheel for rotating it.

3. In a device of the character described, the combination of a main casting having two chambers therein separated from each other, a rotary wheel in one of said chambers, means connected with the other of said chambers for directing a jet of water against said wheel for rotating it, an electric alarm device supported on the side of said casing at the end of said other chamber, and means controlled by the pressure of water therein for operating said electric alarm device, said jet directing means constituting the vent for said other chamber.

In testimony whereof I have hereunto set my hand, in the presence of two subscribing witnesses.

GEORGE I. ROCKWOOD.
